Inventor:
Albert E. Berdon
By G. L. Braggett.

UNITED STATES PATENT OFFICE.

ALBERT E. BERDON, OF DETROIT, MICHIGAN.

CONDENSER.

Application filed May 29, 1922. Serial No. 564,293.

To all whom it may concern:

Be it known that I, ALBERT E. BERDON, citizen of the United States, residing at Detroit, in the county of Wayne and State 5 of Michigan, have invented a certain new and useful Improvement in Condensers, of which the following is a full, clear, concise, and exact description.

My invention relates to condensers, the 10 condensers of my invention being of particular service when employed in flexible cords that serve to connect radio receiving equipment with lamp sockets, although the invention is not to be limited to any particular use to which it may be put.

The condenser of my invention includes two assembled co-axial conduits, two wire conductors, one passing through the bore of each conduit, two condenser plates between 20 said conduits each having one of said wires individual thereto and connected therewith, and a dielectric between said plates and maintaining them in spaced apart relation.

In the preferred embodiment of my invention tangs are stamped from the condenser plates, these tangs extending away from each other and being received in notches that are formed in the adjacent faces of the conduits. The adjacent ends of the 30 conduits are desirably flanged and a band preferably surrounds these flanges to seal the space between the same and to clamp the flanges close together whereby the condenser plates are held in fixed relative positions.

The invention will be more fully explained by reference to the accompanying drawing in which Fig. 1 is a longitudinal sectional view showing the preferred embodiment thereof; Fig. 2 is a side elevation on a smaller scale; Fig. 3 is a view on line 3—3 of Fig. 1; Fig. 4 is a perspective view illustrating one condenser plate and its wire in separated relation; and Fig. 5 is a perspective view illustrating one of the flanged 45 conduits.

Like parts are indicated by similar characters of reference throughout the different figures.

The conduits 1 and 2 are tubelike and are arranged to be co-axial. The adjacent ends of the conduits are formed with flanges 3 and 4. The condenser includes two circular metallic plates 5 and 6 that are separated by a solid dielectric 7 of mica or other suitable material. A band 8 surrounds the flanges and has its edge portions inwardly

bent into clamping engagement with the flanges as indicated at 9. The edges of the flanges are desirably chamfered to conform to the bends of the band. By the assembly thus effected, the condenser plates, the dielectric therebetween, and the conduits are firmly clamped in assembly.

To further guard against the shifting of the condenser plates and to afford a convenient means of attaching their wires 10 and 11 thereto, said condenser plates are formed with tangs 12 and 13 stamped thereon and which are respectively received in notches 14 and 15 formed in the adjacent 60 faces of the conduits. The lateral walls of the notches engage the tangs and prevent the shifting of the condenser plates that have such tangs.

The bores of the conduits are desirably 75 sufficiently large to contain the wires with the serving thereon. The inner ends of the wires are bared and pass through openings 16 formed in the tangs, lumps of solder 17 applied to the inner ends of the wires serving to maintain them in firm mechanical and 80 electrical connection with the tangs.

The entire condenser structure is rendered 85 water proof and moisture proof by the band 8 at the space between the adjacent faces of the conduit flanges and by the serving around the wires that fills the bores of the conduits. I have not deemed it necessary to illustrate the plug by which the flexible 90 wires 10 and 11 are brought into electrical connection with the lamp socket, nor the terminal plug or tag by which the wires are connected with the receiving instrument.

While I have herein shown and particularly described the preferred embodiment of 95 my invention I do not wish to be limited to the precise details of construction shown as changes may readily be made without departing from the spirit of my invention, but having thus described my invention I claim 100 as new and desire to secure by Letters Patent the following:

1. A condenser including two co-axial flanged conduits with the flanges thereof 105 slightly spaced apart; two wire conductors, one passing through the bore of each conduit; two condenser plates between said flanges each having one of said wires individual thereto and having a tang thereon with which such wire is connected, the tangs 110 extending away from each other and being received in notches that are formed in the

adjacent faces of said conduits; a solid dielectric between said plates and maintaining them in spaced apart relation; and a band surrounding said flanges and having its edge portions bent into clamping engagement therewith whereby the condenser plates are held in fixed relative positions.

2. A condenser including two co-axial conduits; two wire conductors, one passing through the bore of each conduit; two condenser plates between said conduits each having one of said wires individual thereto and having a tang thereon with which such wire is connected, the tangs extending away from each other and being received in notches that are formed in the adjacent faces of said conduits; a solid dielectric between said plates and maintaining them in spaced apart relation; and a band surrounding said conduits and having its edge portions bent into clamping engagement therewith whereby the condenser plates are held in fixed relative positions.

25 3. A condenser including two assembled co-axial flanged conduits with the flanges thereof slightly spaced apart; two wire con-

ductors, one passing through the bore of each conduit; two condenser plates between said flanges each having one of said wires individual thereto and having a tang thereon with which such wire is connected, the tangs extending away from each other and being received in notches that are formed in the adjacent faces of said conduits; and a solid dielectric between said plates and maintaining them in spaced apart relations. 35 36

4. A condenser including two assembled co-axial conduits; two wire conductors, one passing through the bore of each conduit; two condenser plates between said conduits each having one of said wires individual thereto and having a tang thereon with which such wire is connected, the tangs extending away from each other and being received in notches that are formed in the adjacent faces of said conduits; and a solid dielectric between said plates and maintaining them in spaced apart relation. 40 45

In witness whereof, I hereunto subscribe my name this 22nd day of May A. D., 1922.

ALBERT E. BERDON.
